HAIRPIN

Ralph T. Ross, Grass Valley, Calif.

Application April 19, 1945, Serial No. 589,214

1 Claim. (Cl. 132—50)

This invention relates to hair pins which are provided with means for retarding the disengagement and subsequent loss of the pin from the hair.

An object of the invention is to provide a hair pin that will not gouge into the scalp when worn or inserted into the hair.

Another object of the invention is to provide a hair pin that will create a pressure on the hair and scalp and thus resist the tendency of the pin to work out of the hair.

With the above and other objects and advantages in view the invention consists in the novel features of construction, combination and arrangement of parts to be hereinafter more fully described, claimed and illustrated in the accompanying drawing, in which:

Fig. 1 is a side view of an embodiment of the invention when in proper position on the scalp.

Fig. 2 is a top plan view.

Fig. 3 is a perspective view, and

Fig. 4 is a side view in reversed position to that shown in Fig. 1.

Referring now more in detail to the drawing wherein similar characters of reference indicate corresponding parts in the several views, 5 designates the hair pin embodying the invention, which is made of wire or any other suitable material.

The pin 5 is bent at the crown 7 to form two prongs or tines 9 and 11, which are arranged in approximately parallel relation to each other.

The prongs 9 and 11 are provided with straight portions 13 and 15 for approximately one-third of their entire length.

The straight portions 13 and 15 at the points 17 and 19 are inclined upwardly to 21 and 23, and then inclined downwardly at 25 and 27 at a lesser degree to form the shallow arcuate shaped portions 29 and 31.

The portions 29 and 31 terminate at the points 33 and 35 to form inclined portions 37 and 39, which in turn terminate at the points 41 and 43 to form straight portions 45 and 47, which extend to the ends of the prongs 9 and 11.

The pin 5 when placed on a flat surface, or on the contour of the scalp, as shown in Fig. 1, has but two points of contact, the arcuate portions 29 and 31 and the crown 7. These points of con-

tact are relatively spaced and equally distanced below a line drawn parallel therewith and contacting the points 21 and 23 of the pin.

With the portions 45 and 47 thus raised beyond the contour of the scalp, the ends of the prongs will not dig or gouge into the scalp and annoy the wearer.

As shown in Fig. 4, the pin can also be used in a reverse position and the points of contact will be the points 25 and 27 and the straight portions 45 and 47. Few advantages of the pin will be lost but in this instance the points will gouge the scalp and will not be as comfortable to wear.

Therefore, when the pin is in position either as shown in Fig. 1 or Fig. 4, the hair will fall into the arcuate shaped portions or the humps formed in the prongs and thus be retained more securely in the hair.

The form of the pin admits of ready insertion into the hair and against accidental displacement from the hair.

It will be understood, therefore, by those skilled in the art that the embodiment of the invention herein disclosed accomplishes the objects of the invention. It also has other advantages than those herein particularly referred to, also that various changes and modifications may be made without departing from the spirit of the invention, and since the embodiment disclosed herein is being only illustrative of the device, the invention is not to be understood as restricted thereto, since this may be modified within the scope of the appended claim without departing from the spirit and scope of the invention.

Having thus described the invention, what is claimed as new and desired to be secured by Letters Patent is:

A device of the character described, comprising a single strand of wire bent at its medial point to form two substantially parallel prongs, said prongs having straight portions extending for approximately one-third of the length of the prongs, upwardly inclined portions merging into depending arcuate shaped portions, and upwardly inclined portions merging into straight portions to more firmly engage the hair on a human head.

RALPH T. ROSS.
